UNITED STATES PATENT OFFICE.

HARRY H. RICHARDSON, OF BEAVERFALLS, PENNSYLVANIA.

COMBINATION SQUARE AND LEVEL.

SPECIFICATION forming part of Letters Patent No. 705,867, dated July 29, 1902.

Application filed February 26, 1902. Serial No. 95,710. (No model.)

To all whom it may concern:

Be it known that I, HARRY H. RICHARDSON, a citizen of the United States of America, residing at Beaverfalls, in the county of Beaver 5 and State of Pennsylvania, have invented certain new and useful Improvements in Combination Squares and Levels, of which the following is a specification, reference being had therein to the accompanying drawings.

10 This invention relates to certain new and useful improvements in combination squares and levels, and relates more particularly to that class used by machinists.

The present invention has for its object to 15 provide a square with a removable blade that may be secured to either side of the body portion or attached to the center thereof, said blade being slidably mounted upon the body portion in order to permit the lineal adjustment of the same.

The herein-described invention further contemplates to provide a square of the above-described character wherein the blade will be securely clamped to either side of the body portion or firmly retained in the center thereof.

25 A still further object of my invention is to construct a square in such a manner as to bring the blade in a position that will be flush with either side of the body portion of the square, thus permitting the square to be brought against the surface of the work, thereby gaining an advantage over the square with the blade in the center of the body.

With the above and other objects in view 35 the invention consists in the novel construction, combination, and arrangement of parts to be hereinafter more fully described, and specifically pointed out in the claims.

In describing the invention in detail reference is had to the accompanying drawings, forming a part of this specification, and wherein like numerals of reference indicate like parts throughout the several views, in which—

40 Figure 1 is a perspective view of my improved square, showing the blade secured to one side thereof. Fig. 2 is a top plan view of the square-body with the blade removed therefrom. Fig. 3 is a vertical sectional view showing the blade secured centrally in the square.

45 Fig. 4 is an end elevation of the square-body with the blade removed therefrom. Fig. 5 is

a perspective view of the clamping-jaws carrying the screw-threaded shank.

In the drawings the reference-numeral 1 indicates the body portion of the square, having outwardly-extending flanges 22, said body portion having an inclined face 3, which extends at an angle of forty-five degrees, and the back of the square 4 extends at an angle of ninety degrees or extends at a right angle to the upper portion of the square. The lower portion of the body portion, as shown at 5, forms a V shape and describes an angle of forty-five degrees, as shown in Fig. 1 of the drawings. The body portion of the square 65

has formed thereon shoulders 66 on each side, and the upper walls of the square 7 have formed therein the central slot 8. In these upwardly-extending walls 7 are also formed openings 9, which communicate with the central slot 8. A central opening 10 extends downwardly into the body portion of the square, and the walls of said opening are slightly beveled, as shown at 11, and an opening 12 is formed in the body portion of the square below the said central opening.

Clamping-jaws 14 are secured in the openings 9, and a screw-threaded shank portion 15 of the clamping-jaws extends downwardly in the central opening 10, the beveled sides 16 75 engaging the beveled walls 11 of the square. An interiorly-screw-threaded sleeve 17 engages the screw-threaded shank 15, this screw-threaded sleeve 17 being seated and operating in the opening 12 formed in the square. 80 This screw-threaded sleeve 17 has formed therein an annular recess 18 to receive the spring 19. The said clamping-jaws carry dovetails 20 on each side, these dovetails 20

projecting outwardly from the sides 7 of the body portion. Dovetail projections 21 are also formed on the inner face of one of the clamping-jaws, these dovetails 20 and 21 being adapted to engage in the dovetailed groove 22 of the blade 23. A cylindrical casing 24 is also formed integral with the square and has an opening 25 formed therein. In this cylindrical casing 24 is placed a spirit-level 26, said casing being closed by means of the screw-threaded plug 27.

100 The operation of my improved combination-square is as follows: The blade is preferably

secured on one side of the square and engages the dovetail, being slidingly secured thereon. When secured in position, the interiorly-screw-threaded sleeve is turned, thereby drawing the screw-threaded shank of the clamping-jaws downwardly. By this operation a double action is obtained upon the blade—*i. e.*, first the blade is drawn downwardly firmly against the one of the shoulders 6, and, secondly, by the closing of the jaws the engaging face of the blade is drawn firmly against the outer face of the square, thereby obtaining a locking connection therewith. It will be further noted that when in this position the outer face of the square and the outer face of the blade are flush with one another, permitting the square to be brought up close to the work to be performed and preventing a shadow, which is apt to confuse accurate measurements when it is desired to make close calculations. When it is desirable to place the blade in the central portion of the square, the latter engages the dovetail 21, and by operating the sleeve as heretofore described the clamping-jaws will firmly grasp the blade and retain the same in proper position. The dotted lines in Fig. 3 of the drawings indicate the position of the blade in relation to the jaws when placed on either side of the square.

The many advantages obtained by the use of my improved combination square and level will be readily apparent from the foregoing description taken in connection with the accompanying drawings.

It will be noted that various changes may be made in the details of construction without departing from the general spirit of my invention.

Having fully described my invention, what I claim as new, and desire to secure by Letters Patent, is—

1. In a square, the combination of the body portion provided with a series of blade-seats

the adjacent ones of which are separated by intervening walls, a removable blade, and a single clamp for holding the blade in either of the seats.

2. In a square, the combination of the body portion provided on its opposite sides with blade-seats and a central seat in its upper edge, a removable blade, and a clamp provided in its upper end with a slot, said clamp adapted to engage and retain the said blade when arranged in either of the said seats.

3. In a square the combination of the body portion provided with a central seat in its upper edge, and a seat on each side thereof, said body portion provided with a vertically-arranged opening communicating with the said central seat, a clamp provided with a screw-threaded shank, arranged in the said opening and having its upper end provided with a slot registering with the said longitudinal seat, a screw-threaded sleeve on said shank, a removable blade, and means whereby the said clamp will retain the said blade in each of the said seats.

4. In a square, the combination with a body portion provided with a central slot and formed on its opposite sides with shoulders, of a blade formed on one of its sides with a dovetail slot, said blade adapted to be received in the said central slot and shoulders of the body portion, clamping-jaws to engage the said blade and formed with a screw-threaded shank secured in said body portion, said clamping-jaws formed with dovetail extensions on their outer sides and one of them with such extension on its inner side, and a screw-threaded sleeve secured to said screw-threaded shank.

In testimony whereof I affix my signature in the presence of two witnesses.

HARRY H. RICHARDSON.
